UNITED STATES PATENT OFFICE.

ANDY E. TANGEN, OF BISMARCK, DAKOTA TERRITORY.

FASTENING FOR TOOL-HANDLES.

SPECIFICATION forming part of Letters Patent No. 224,244, dated February 3, 1880.

Application filed November 6, 1879.

To all whom it may concern:

Be it known that I, ANDY E. TANGEN, of Bismarck, in the county of Burleigh and Territory of Dakota, have invented a new and Improved Fastening for Tool-Handles, of which the following is a specification.

The object of my invention is to furnish a firm and easily-applied device for fastening handles to axes and other tools, and which 10 will also allow the handle to be quickly and easily removed without injury to the ax.

The invention consists in fastening the handle in the eye of the ax or tool by means of spring-straps adapted to clasp the ends of the 15 handle inserted in the eye, a bolt inserted into the eye from the side or end opposite the handle, so as to engage the said spring-straps, and a heart-shaped piece placed over the eye on the same side, which furnishes a bearing for 20 the head of the bolt, all arranged in the manner fully described in connection with the drawings.

In the accompanying drawings, Figure 1 is a sectional side elevation of my improvement 25 applied to connecting the ax and handle together. Fig. 2 is a perspective view of the spring-straps; and Fig. 3 is a view of the heart-shaped piece which supplies a bearing for the head of the bolt used in connection with my 30 improved fastener.

Similar letters of reference indicate corresponding parts.

Referring to the drawings, A is the ax, B is the eye, and C is the ax-handle. D D are 35 two spring-straps, having the ends *a a* connected together by a right-angular web, *b*, while the free ends are provided with inwardly-turned prongs *c c*. In web *b* is a screw-threaded hole, *d*.

E is a bolt, which is adapted to be screwed.

in hole *d* of web *b*. F is a heart-shaped piece, provided with a counterbored hole, *e*, for the bolt E, and a heart-shaped projecting portion, *f*, on its under side, which is adapted to be entered in the eye B, while the projecting 45 flange *g* bears upon the part of the ax immediately surrounding the eye B.

The manner of using the device is as follows: The end of the handle C is placed between straps D D; then the ends *a a* and web 50 *b*, with the handle are inserted in the eye B, and the handle is driven in so that the sides of the eye will press the straps D D against the sides of the handle and force the prongs *c* into the wood, for the purpose of giving the 55 straps a firm hold of the handle within the eye. The heart-shaped piece F is then applied to the opposite end of the eye, and the bolt E inserted through hole *e*, and screwed into hole *d* of web *b*, whereby the handle is 60 drawn into the eye and the heart-shaped piece pressed firmly down on its seat, so that a connection is made, by means of bolt E and straps D D, between the handle and piece F, and the handle is firmly fastened to the ax in such a 65 manner that it can be easily and quickly tightened when necessary, and can also be removed without injury to the ax.

Having thus described my invention, what I claim as new, and desire to secure by Letters Patent, is—

An improved device for fastening handles, consisting of spring-straps D D, provided with web *b*, screw-bolt E, and heart-shaped piece F, constructed, arranged, and operated 75 in the manner substantially as described.

ANDY EVENSEN TANGEN.
